[57] CLAIM

The ornamental design for housing for computerized diagnostic system, as shown and described.

DESCRIPTION

Housing for computerized diagnostic system is, in one embodiment, intended for use as a portable diagnostic system to aid troubleshooting and maintenance of electronic systems.

FIG. 1 is a front, right side, top perspective view of a housing for computerized diagnostic system showing my new design;

FIG. 2 is a rear, left side, top perspective view thereof;
FIG. 3 is a front elevational view thereof;

FIG. 4 is a rear elevational view thereof;

FIG. 5 is a right side elevational view thereof;

FIG. 6 is a cross-sectional view taken along line 6—6 of FIG. 5 showing the contour of the recess in FIG. 5;

FIG. 7 is a left side elevational view thereof;

FIG. 8 is a top plan view thereof; and,

FIG. 9 is a bottom plan view thereof.
